UNITED STATES PATENT OFFICE.

ALEX MELNICKZAK, OF CAMDEN, NEW JERSEY.

AEROPLANE.

1,228,227.

Specification of Letters Patent. Patented May 29, 1917.

Application filed December 18, 1916. Serial No. 137,627.

To all whom it may concern:

Be it known that I, ALEX MELNICKZAK, a subject of the Emperor of Austria, residing at Camden, in the county of Camden and

5 State of New Jersey, have invented certain new and useful Improvements in Aeroplanes, of which the following is a specification.

This invention relates to aeronautical apparatus and has special reference to an apparatus of the helicopter type designed for use by a single person to facilitate observations of the surrounding terrain.

One important object of the invention is 15 to provide an improved general construction of devices of this character.

A second important object of the invention is to provide an improved construction of such a device whereby the helicopters 20 may be actuated by either foot power or manually or both, the arrangement being such as to permit either power to run slower than the other or stop altogether without affecting the operation of the helicopters to 25 stop the same.

With the above and other objects in view, as will be hereinafter apparent the invention consists in general of certain novel details of construction and combinations of 30 parts hereinafter fully described, illustrated in the accompanying drawing, and specifically claimed.

In the accompanying drawing, like characters of reference indicate like parts in the 35 several views, and:

Fig. 1 is a front elevation of the device.

Fig. 2 is a plan thereof.

Fig. 3 is a section on the line 3—3 of Fig. 1.

40 Fig. 4 is a section on the line 4—4 of Fig. 1.

Fig. 5 is a detail section through the main drive shaft.

Fig. 6 is a section on the line 6—6 of 45 Fig. 5.

In the embodiment of the invention herein illustrated there is provided a breast plate 10 preferably formed of leather or other like material and secured firmly to this breast 50 plate are the vertical frame members 11, rivets 12 being preferably employed for securing purposes. These frame members are curved at their top ends to provide shoulder engaging hooks 13 and on the extremities of 55 these hooks are connected securing straps 14.

The breast plate is also provided with a waist strap 15 and leg straps 16. In this manner the device is firmly secured to the body of the user.

Extending across the breast plate 10 and 60 firmly secured to the members 11 is a tubular bearing sleeve 17 and at each end of this sleeve but spaced therefrom is a similar bearing sleeve 18, the latter being secured to the members 11 by braces 19. Through the 65 sleeves 17 and 18 extends a main shaft 20 which projects from the outer ends of the sleeves 18 and carries on the outer ends the bevel gears 21. These bevel gears 21 mesh with similar gears 22 mounted on stub 70 shafts 23 journaled in bearing brackets 24 carried by the sleeves 18. On the upper 75 ends of the shaft 23 are fixed the hubs 25 of helicopters having propeller blades 26.

Between the sleeve 17 and each sleeve 18 75 there is mounted fixedly on the shaft 20 two pairs of ratchet wheels 27 and adjacent each of the ratchet wheels 27 is a freely revolv. 80 ing sprocket 28 carrying a pawl 29.

Extending forwardly from the members 80 11 are brackets 30 having bearings 31 at their forward ends and through these bearings extends a shaft 32 having sprockets 33 fixed thereon and connected by chains 34 with one of the sprockets 28 at each end of 85 the shaft 20. On this shaft 32 are also handle cranks 35 so that the shaft 32 may be rotated by the user and thereby the shaft 20 actuated to drive the helicopters, it being noted that the pawl and ratchet mechanism 90 is arranged to cause actuation of the shaft 20 in such direction that the helicopters will tend to lift the user.

Below the shaft 20 is a sleeve 36 fixed to the members 11 and through this sleeve extends a shaft 37 having sprockets 38 fixed thereon which are connected to the remaining sprockets 28 by chains 39. On this shaft 37 are also fixed cranks 40.

At the bottom ends of the members 11 is 100 fixed a bearing 41 wherethrough runs a double crank shaft 42 carrying pedals 43 which are connected to the cranks 40 by links 44.

In order to afford means for locking the 105 pawls when desired so that the ratchets may actuate the shaft 20 in either direction there are provided pins 45 which may be inserted in suitable holes in the sprockets to hold the pawls against disengagement.

By means of this construction no difficulty is experienced in operation, no matter whether the operator's hands work faster or slower than his feet, the maximum effect being, of course, obtained when both hands and feet work synchronously.

In operation the device is strapped onto a man so that he can work the pedals and upper crank shaft which in turn work the 10 helicopters and thus raise him rapidly into the air. When the desired height is reached he may observe a broad expanse of territory and by running the helicopters at a proper speed may remain practically stationary. 15 He may also carry up with him suitable communicating means such as a telephone and in order to assist him a suitable aerostat 46 may be attached to the device.

There has thus been provided a simple 20 and efficient device of the kind described and for the purpose specified.

It is obvious that many minor changes may be made in the form and construction of the invention without departing from 25 the material principles thereof. It is not therefore desired to confine the invention to the exact form herein shown and described but it is wished to include all such as properly come within the scope claimed.

Having thus described the invention, what is claimed as new, is:—

1. In a flying machine, the combination with a breast plate, means to secure the breast plate to the body of a person, a shaft 35 carried by the breast plate and extending transversely of the body, a pedal operated shaft supported from said breast plate, a manually operated shaft supported from said breast plate, helicopters driven by the 40 first shaft on opposite sides of the breast plate and means to connect the first shaft to each of the other shafts, said means being arranged to permit either of the last-

mentioned shafts to rotate faster than the other in one direction.

2. In a flying machine, the combination with a breast plate, means to secure the breast plate to the body of a person, a shaft carried by the breast plate and extending 50 transversely of the body, a pedal operated shaft supported from said breast plate, a manually operated shaft supported from said breast plate, helicopters driven by the first shaft on opposite sides of the breast 55 plate, sprockets freely revoluble on the first shaft, sprockets fixed to the last two shafts and connected by chains with the first sprockets, a ratchet fixed to the first mentioned shaft adjacent each of the first sprockets, and a pawl on each of the first sprockets 60 coacting with the adjacent ratchet.

3. In a flying machine, the combination with a breast plate, means to secure the breast plate to the body of a person, a shaft carried by the breast plate and extending 65 transversely of the body, a pedal operated shaft supported from said breast plate, a manually operated shaft supported from said breast plate, helicopters driven by the first shaft on opposite sides of the breast 70 plate, sprockets freely revoluble on the first shaft, sprockets fixed to the last two shafts and connected by chains with the first sprockets, a ratchet fixed to the first-mentioned shaft adjacent each of the first sprockets, a pawl on each of the first sprockets 75 coacting with the adjacent ratchet and releasable means to lock said pawls on their ratchets.

In testimony whereof I affix my signature in the presence of two witnesses.

ALEX MELNICZAK.
